CLAIM

The ornamental design for a folding table, as shown and described.

DESCRIPTION

FIG. 1 is a front perspective view of a folding table in a retracted position showing our new design:

FIG. 2 is another perspective view thereof showing the design in an extended position;

FIG. 3 is a top plan view thereof showing the design in a retracted position;

FIG. 4 is a front elevation thereof;

FIG. 5 is a left side elevation thereof;

FIG. 6 is a top plan view thereof in an extended position;

FIG. 7 is a front elevation thereof; and,

FIG. 8 is a left side elevation thereof in an extended position.
